US0D1083497S

(12) **United States Design Patent** (10) **Patent No.:** **US D1,083,497 S**
(45) **Date of Patent:** **** Jul. 15, 2025**

(54) **COVER FOR CONTAINER**

(71) Applicant: **Universal Trim Supply Co., Ltd.**, New Taipei (TW)

(72) Inventors: **Aly Khalifa**, Raleigh, NC (US); **Shih-Sheng Yang**, Taipei (TW); **Chih-Wei Yang**, Taipei (TW)

(73) Assignee: **Universal Trim Supply Co., Ltd.**, New Taipei (TW)

(**) Term: **15 Years**

(21) Appl. No.: **29/905,078**

(22) Filed: **Oct. 17, 2023**

(51) LOC (15) Cl. **07-02**

(52) U.S. Cl. **D7/392.1**
USPC ....

(57) **CLAIM**

The ornamental design for a cover for container, as shown and described.

DESCRIPTION

FIG. 1 is a top, front, right side perspective view of a cover for container, showing our new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, front, right side perspective view of the cover for container of FIG. 1 shown in a condition of use.

The broken lines in the drawings depict portions of the cover for container that form no part of the claimed design. The broken lines showing the container in the drawings, and showing the electronic device in FIG. 9, represent environmental subject matter that form no part of the claimed design.

1 Claim, 9 Drawing Sheets
